DESIGN FOR A COAT

Jules Freedman, New York, N. Y.

Application May 29, 1947, Serial No. 139,367

Term of patent 3½ years

(Cl. D3—4)

To all whom it may concern:

Be it known that I, Jules Freedman, a citizen of the United States of America, residing in New York city, county of Kings, and State of New York, have invented a new, original, and ornamental Design for a Coat, of which the following is a specification, reference being had to the accompanying drawing, forming part thereof wherein,

The essential feature of my design resides in the combination, on the coat disclosed, of the specific curved yoke ornamentation of pockets and stitching with the harmonizing curved skirt pockets, all as shown.

I claim:

The ornamental design for a coat, substantially as shown and described.

JULES FREEDMAN.
